US0D1012960S

(12) **United States Design Patent** (10) **Patent No.:** **US D1,012,960 S**
Hicks et al. (45) **Date of Patent:** **** Jan. 30, 2024**

(54) **DISPLAY SCREEN WITH GRAPHICAL USER INTERFACE**

(71) Applicant: **LIFE TECHNOLOGIES CORPORATION**, Carlsbad, CA (US)

(72) Inventors: **Justin Hicks**, Eugene, OR (US);
Matthew Shallice, Eugene, OR (US);
Laurel Stone, Eugene, OR (US);
Charysse Archer, Eugene, OR (US)

(73) Assignee: **LIFE TECHNOLOGIES CORPORATION**, Carlsbad, CA (US)

(**) Term: **15 Years**

(21) Appl. No.: **29/800,887**

(22) Filed: **Jul. 23, 2021**

Related U.S. Application Data

(62) Division of application No. 29/625,252, filed on Nov. 8, 2017, now Pat. No. Des. 928,186, which is a division of application No. 29/453,150, filed on Apr. 25, 2013, now Pat. No. Des. 802,608.

Primary Examiner — Rachel A. Voorhies

(57) **CLAIM**

The ornamental design for a display screen with graphical user interface, as shown and described.

DESCRIPTION

FIG. 1 is a front view of a first embodiment of a display screen with graphical user interface showing our new design; and,

FIG. 2 is a front view of a second embodiment of a display screen with graphical user interface showing our new design.

The outermost dash-dash broken line rectangle depicts a display screen and forms no part of the claims design. The remaining dash-dash and dot-dot broken lines illustrate portions of the graphical user interface that form no part of the claimed design.

1 Claim, 2 Drawing Sheets
